UNITED STATES PATENT OFFICE.

GILBERT E. ALPHIN, OF MOUNT OLIVE, NORTH CAROLINA.

WINDOW FIXTURE.

Application filed February 1, 1926. Serial No. 85,265.

The present disclosure of the invention relates to a novel support for a window curtain, a drapery and a shade, and while the device is preferably constructed for supporting all three of these members, it could of course be used to suspend only one or two of them.

The device includes a rod for the reception in the hem of a curtain or drapery, the ends of the rod being turned rearwardly toward the frame and adapted for reception in the end portions of the hem, the principal object of the invention being to provide novel means for holding these end portions of the hem against accidental sliding from the ends of the rod.

A further object is to provide the device with members having multiple functions, one of these functions being to hold the ends of the curtain or drapery hem in proper place, while the other function is to support a shade or curtain.

The rod is formed of relatively adjustable sections and a still further aim of the invention is to make unique provision for slidably connecting said sections.

With the foregoing in view, the invention resides in the novel subject matter hereinafter described and claimed, the description being supplemented by the accompanying drawings.

Figure 1 is a top plan view of the invention applied to a frame such as a window frame, parts of the drapery being broken away, as well as parts of the supporting device.

Fig. 2 is a front elevation of the parts shown in Fig. 1.

Figs. 3 and 4 are detail sectional views on the correspondingly numbered lines of Figs. 1 and 2 respectively.

Fig. 5 is a diagrammatic top plan view illustrating the manner in which two of the improved supports may be used when the window is of exceptional width.

In the drawings above briefly described, the numeral 6 designates a rod whose end portions are turned rearwardly to provide supporting arms 7, said rods being preferably formed of strip metal. The metal at the inner ends of the arms 7, is curved horizontally inward as at 8 and then extends forwardly as indicated at 9, providing an additional pair of arms which are inwardly spaced from and parallel with the attaching arms 7. These arms 9 are formed with

any desired number of openings 10, some of which may receive the pintles of a shade roller 11 while others may receive the ends of a curtain rod 12. At the front ends of the arms 9, the metal is curved outwardly as indicated at 13 and is then extended rearwardly to provide a pair of clamping arms 14 which are cooperable with the arms 7 to yieldably hold the ends of a hem 15, formed at the upper edge of a drapery or curtain 16, to be supported by the rod 6. The arms 14 have an inherent tendency to spring outwardly into contact with the arms 7 and thus, when the hem 15 is rearwardly pulled between these two sets of arms, said hem will be effectively held. Thus, there is no danger of the ends of the hem sliding forwardly away from the window frame and onto the main body portion of the rod 6.

The curved portions 9 of the device may be connected with a window frame or analogous frame, in any desired manner. I prefer however to provide crank-like supporting screws 17 for this purpose.

In constructing the device, provision is preferably made for permitting adjustment thereof according to the width of the frame upon which it is to be mounted. In accomplishing this end, I form the rod 6 of two slidably overlapped sections. Both of these sections pass through flat collars 18, each of which is preferably formed by bending a metal strip in the manner shown in Fig. 4. These collars are located adjacent the inner ends of the rod sections, and said ends are bent laterally around side members of the collars as indicated at 19. Thus, one collar is connected with one section of the device and slidably engages the other section, and vice versa.

By the novel construction shown and described, or a substantial equivalent thereof, a device is produced which is exceptionally simple and inexpensive, yet is efficient and in every way desirable, particular attention being directed to the unique means for holding the ends of the hem 15 in proper position upon the attaching arms 7. Further attention is also invited to the fact that the portions 9-13-14, form combined or multi-function members which not only hold the hem ends in place, but act to support a curtain pole 12, a shade roller 11 or some analogous member. Attention may also be directed to the simple and inexpensive construction which has been disclosed for slid-

ably connecting the two sections of the rod 6.

When the device is to be used in connection with a frame of unusual width, two of them may be employed as diagrammatically shown in Fig. 5. Then, the hem which is designated at 15^a, will have an opening 15^b formed at its central portion, through which the inner, adjacent, attaching arms 7, may pass.

10 Excellent results have been obtained from the construction disclosed and it is therefore preferably followed. However, within the scope of the invention as claimed, numerous variations may be made.

15 I claim:

1. A support of the class described comprising a horizontal rod for reception in a hem, the end portions of said rod being rearwardly turned, forming attaching arms which are receivable in the end portions of the hem, and combined supporting and clamping members formed from a forwardly and rearwardly bent extension of said attaching arms, said members serving to clamp the arm-containing portions of the hem against the arms and having means to engage and support a shade or curtain carrying member, or both. 25

2. A support of the class described comprising a horizontal rod for reception in a hem, the end portions of said rods being rearwardly turned, forming attaching arms which are receivable in the end portions of the hem, the metal at the rear ends of the

attaching arms being bent inwardly and forwardly, providing additional arms which are inwardly spaced from said attaching arms and are formed with means to engage a shade or curtain carrying member, or both the metal at the front ends of said additional arms being bent outwardly and rearwardly providing spring arms at the inner sides of the attaching arms and active to hold the arm-receiving portions of the hem against sliding from said attaching arms. 35 40 45

3. A support of the class described comprising a horizontal rod for reception in a hem, the end portions of said rod being rearwardly turned forming attaching arms which are receivable in the end portions of 50 the hem, said arms being bent to form jaws coactive with the inner sides of said arms to clamp said end portions of the hem against sliding from said arms.

4. A support of the class described comprising a horizontal rod for reception in a hem, the end portions of said rod being rearwardly turned forming attaching arms which are receivable in the end portions of 55 the hem, and combined supporting and clamping members formed from a forwardly and rearwardly bent extension of said attaching arms, the terminals of said members serving to clamp the arm-containing portions of the hem against the arms. 60 65

In testimony whereof I have hereunto affixed my signature.

GILBERT E. ALPHIN.
